UNITED STATES PATENT OFFICE.

BENJAMIN H. KLEIN, OF DELAWARE, OHIO.

WASHING-MACHINE.

SPECIFICATION forming part of Letters Patent No. 716,843, dated December 23, 1902.

Application filed May 6, 1901. Serial No. 58,925. (No model.)

To all whom it may concern:

Be it known that I, BENJAMIN H. KLEIN, a citizen of the United States, residing at Delaware, in the county of Delaware and State of Ohio, have invented new and useful Improvements in Washing-Machines, of which the following is a specification.

My invention relates to machines for washing fabrics of the kind in which the water or other cleansing fluid is alternately sucked and forced through the meshes of the fabric by the action of a reciprocating cup or a plurality of such cups; and it consists in the novel features hereinafter described, and more particularly pointed out in the claims.

In the drawings, Figures 1 and 2 are perspective views, respectively, of the entire machine and the central standard or support.

A is the standard or support, having a handhold B, a pivot C, and guides L L. This standard or support is preferably formed of a single strip of metal bent to form the handhold B and split at the ends to form a number of guides L L. These guides are bent backward parallel to the standard, leaving their ends free. Said guides may also be formed independently and secured rigidly to the standard in any convenient manner, as by welding.

Connected to the standard by means of the pivot C is the lever D, having a convenient handle E and holes M M'. Through the holes M M' and working loosely therein are passed rods F F', bent into inverted-U shape. I prefer to make these rods in the manner indicated; but the precise method is immaterial. The inverted cups G G' G² G³, preferably of heavy sheet metal, are secured by their bottoms to the rods F F' in any convenient manner, the cups first being arranged on the guides L L, as shown, by means of the ears K, which have holes to receive said guides.

The operation of my device is simple. It is placed with the cups on the fabric to be washed in a vessel containing water or other

cleansing fluid, such as gasolene, and held 45 by the handhold B. The lever D is then operated, moving the cups up and down, the cups sliding on the guides L L. The movement of the cups sucks and forces the fluid through the meshes of the fabric, with the effect that foreign matter is rapidly washed out. 50

My device is readily assembled and taken apart, due to the guides being free-ended. By unscrewing the inside nuts the rods F F' may be raised clear and swung outward, when 55 the cups may be lifted off the guides and the whole compactly folded for shipment.

Having fully described my invention, what I claim as new, and desire to secure by Letters Patent, is—

1. In a washing-machine of the kind described, the combination with a standard having at its lower end a plurality of vertical, free-ended guides substantially parallel thereto, and integral therewith, of a plurality of 65 cups movably mounted on said guides, and means for vertically reciprocating said cups, substantially as and for the purposes set forth.

2. In a washing-machine of the kind described, a standard or support having at one end a plurality of free-ended guides, substantially parallel thereto, and integral therewith, substantially as and for the purposes set forth. 70

3. In a washing-machine of the kind described, a standard or support, consisting of a strip of metal bent upon itself at its center to form a handhold, and having its ends upturned to form free-ended guides, substantially as and for the purposes set forth. 75

In testimony whereof I affix my signature in presence of two witnesses.

BENJAMIN H. KLEIN.
